CLAIM

The ornamental design for the air intake manifold, as shown and described.

DESCRIPTION

FIG. 1 is a top right front isometric view of the air intake manifold showing our new design;
FIG. 2 is a front elevation view thereof;
FIG. 3 is a rear elevation view thereof;
FIG. 4 is a top plan view thereof;
FIG. 5 is a bottom plan view thereof;
FIG. 6 is a right elevation view thereof;
FIG. 7 is a left elevation view thereof;
FIG. 8 is a perspective view thereof from a top left rear perspective;
FIG. 9 is a perspective view thereof from a bottom left front perspective; and,
FIG. 10 is a perspective view thereof from a bottom right rear perspective.

The broken lines and the light-grayed-out surfaces of the manifold interior shown in the drawings are for the purpose of illustrating portions of the article and form no part of the claimed design.
